UNITED STATES PATENT OFFICE

PHILIP MUELLER, OF DECATUR, ILLINOIS, ASSIGNOR, BY MESNE ASSIGNMENTS, TO MUELLER CO., OF DECATUR, ILLINOIS, A CORPORATION OF ILLINOIS

CHINA SPOUT

Application filed November 20, 1926. Serial No. 149,740.

The present invention relates to fluid supply fixtures, such as spouts, faucets and other lavatory fixtures or accessories, which are made from china or ceramic material, and 5 has to do more particularly with an improved connection, whereby such fittings may be conveniently connected with water pipes or the like.

As is well known, spouts of ceramic material are liable to crack or fracture, and it is 10 not practicable to thread or similarly form the same for direct connection with the water supply pipe. Moreover, it is desirable to avoid direct contact between the ceramic 15 material and the metal connections, since the two materials are variably expansible, and, moreover, the unyielding character of the connections renders the same liable to fracture the spout when tightened.

20 An object of the invention is to provide a connection which will enable the ceramic spout to be fixedly positioned without danger of breakage, and which will also permit final positioning of the spout after the connections 25 are tightened, to properly direct the same with reference to the tub or basin to which it delivers. It is often necessary to give the spout a final movement after the connections are tightened, and it is desirable to accomplish this without loosening the latter. The 30 present invention has as an object, the provision of a connection which will permit this adjustment.

A further object of the invention is to 35 provide a connection in which there is no direct contact between the metallic parts of the connection and the spout or other ceramic filling.

Other objects of the invention relate to 40 simplicity of construction, convenience in assembly, and facility of operation, and will become apparent as the description proceeds.

The invention comprises broadly, a spout 45 construction having a bore adapted to receive and hold against rotation, a flexible gasket or other element which is relatively soft or yielding as compared to metal. Preferably, the gasket is also held against movement 50 longitudinally of the spout. Within the bore

is positioned a metallic sleeve, which would be freely rotatable, and otherwise movable in the spout, except for the gasket which engages the sleeve, as by receiving the latter in an aperture formed therein. The sleeve 55 snugly fits into the gasket, and thereby is held against independent rotation, and also it is preferred, although not necessary, against movement longitudinally of the spout.

The sleeve is threaded or formed in any 60 equivalent manner for engagement with the supply pipe, and being held fixed in the spout by means of the gasket, it may be rotated by turning the spout, and thereby 65 tightened upon the supply pipe. Rotation of the spout about the supply pipe imparts corresponding rotation to the sleeve, and the latter, when the spout reaches a fixed abutment such as a wall, presses the gasket 70 against a wall of the spout, thereby locking the latter in position.

75 Preferably, the engagement between the spout and gasket is a frictional one, so that the final adjustment of the spout to direct the same properly toward the basin, tub, or other fixture, with which it is used, may be accomplished without releasing the connection. These, and other features of the invention will become clearer as the description 80 proceeds in connection with a preferred form illustrated in the accompanying drawings, wherein:

Figure 1 is a longitudinal vertical sectional view of a ceramic spout connected 85 with a supply pipe by my improved connection.

Figure 2 is a similar view, showing the parts within the spout assembled preliminary to the positioning of the spout upon the 90 supply pipe.

Figure 3 is a longitudinal vertical sectional view showing a somewhat modified construction.

Figure 4 is a view similar to Figure 3, 95 showing a further modification.

Figure 5 is a longitudinal sectional view of the sleeve employed in Figures 1 to 4.

Figure 6 is a transverse sectional view on the line 6—6 of Figure 5.

Figure 7 is a longitudinal sectional view of a modified form of sleeve.

Figure 8 is a transverse section on the line 8-8 of Figure 7.

Figure 9 is a longitudinal sectional view of another form of sleeve.

Figure 10 is a transverse section on the line 10-10 of Figure 9.

Figure 11 is a longitudinal sectional view of still another modification.

Figure 12 is a transverse section on the line 12-12 of Figure 11.

Referring to the drawings for a more detailed description, 10 indicates a ceramic fitting, in the present instance illustrated as a spout intended for use with a tub or basin, the spout having an elongated bore 11 enlarged at the rear end of the spout into a chamber 12. The bore of the spout around the chamber may be curved as at 13 from the smaller bore 11, to form a seat 14 adapted to receive tightly a flexible gasket 15 formed from non-metallic material, which is soft as compared with metal, in order to avoid fracture of the spout.

The rear wall 16 of the spout is formed with an aperture 17 through which the gasket 14 may be inserted by flexing the same, and, as will be understood, when it enters the chamber 12, it immediately expands into its seat 14. The gasket is of sufficient size to fit very snugly in its seat, as illustrated in Figure 2, and due to this close fit, will be held frictionally against free rotation, although if desirable, interengaging means may be formed on the interior of the spout to effect a more positive engagement with the gasket.

Before the gasket is inserted, a metallic sleeve 18 is placed in the chamber 12 through the rear aperture 17, the sleeve being threaded internally as at 19 to fit upon the threaded end of a supply pipe S projecting through an opening 21 in the wall W which may be part of a fixture such as a tub or sink, or the permanent wall of a building to which spouts are not infrequently attached in the more modern installations.

After both the sleeve and the gasket have been introduced into the spout of the chamber 12, the sleeve may be drawn into the central aperture of the gasket, the aperture being so formed as to provide a relatively snug fit for the sleeve, thereby holding the latter against rotative movement relative to the spout. Also, due to the fixed position of the gasket and the close fit of the sleeve therein, the latter is held against longitudinal movement. With the parts thus assembled in the spout, as illustrated in Figure 2, the latter may be positioned upon the supply pipe S. By rotating the spout, the sleeve 19 will be threaded upon the supply pipe, it being borne in mind that the spout is connected with the sleeve through the fixedly posi-

tioned gasket 15. As the sleeve is adjusted on the spout, its flange 23, which constitutes a peripheral means abutting a face of the gasket, will force the latter against the rear wall 16 of the spout and thereby move the spout to position. When the rear end of the spout reaches the wall W, subsequent turning of the spout will cause the sleeve to press the gasket against the wall 16 (Figure 1) thus gripping the latter between the sleeve and wall W, and holding the spout in position.

Should it be found, after sufficient tightening of the connection, that the discharge end of the spout is not accurately directed with respect to the tub or other fixture to which it delivers, the same may be turned readily by application of a moderate amount of force to overcome the frictional resistance between the wall of the spout and the gasket. As illustrated in Figures 5 and 6, the flange 23 of the sleeve which forces the gasket against the rear wall of the spout, is formed with means, such as face corrugations 24, to effect a positive engagement between the sleeve and the gasket, and thereby prevent slippage between the gasket and sleeve as the spout is revolved upon the supply pipe to tighten the connection.

Figures 7 to 12 illustrate various other forms of sleeves which may be used instead of the sleeve 18.

For instance, in the form illustrated in Figures 7 and 8, the sleeve 25 has formed on its periphery, corrugations 26 which, with the corrugations 27 on the flange 28, assist in preventing slippage between the sleeve and gasket.

In Figures 9 and 10, the sleeve 29 has a flange 30, but the same is not formed with means for interlocking with the gasket, such means being provided upon the portion of the sleeve adapted to fit within the gasket, as illustrated by the reference character 31.

Referring to Figures 11 and 12, the sleeve 32 is formed with a plurality of longitudinally extending ribs or keys 33, adapted to interfit with the key-ways which are formed upon the gasket 34.

In Figure 3, there is illustrated a slightly modified form of connection, utilizing the sleeve illustrated in Figures 5 and 6. This connection includes the same elements illustrated in Figures 1 and 2, and which are indicated by corresponding reference characters. Additionally, however, the rear wall 16' of the spout is counter-sunk to provide a seat 35 receiving a second gasket 36. This gasket, as will be observed, is introduced between the end of the sleeve 18 and the wall W. It is also interposed between the wall 16 of the spout and the wall W, and is preferably engaged by both the sleeve 18 and the spout. This gasket closely fits around the supply pipe 21, and assists in preventing

leakage between the sleeve 18 and the supply pipe.

The form of the invention illustrated in Figure 4 differs from the construction illustrated in Figure 3, in that, instead of the seat 35 having walls at substantially right angles to one another, a seat of slightly different form is provided in the rear wall of the spout. The rear wall 16" is bevelled 10 toward the aperture 17", and a gasket 38, tapering toward its periphery and conforming to the shape of the seat, is interposed between the spout and wall, and, also, preferably, between the rear end of the sleeve 18 and the wall. This gasket closely surrounds the supply pipe 21, and it may be clamped in position by the spout alone, or, as illustrated, by both the spout and the end of the connection sleeve 18. As will be obvious, the advantages set forth with respect to the form of the invention illustrated in Figures 1 and 2, are equally obtainable by the forms shown in Figures 3 and 4, and it will further be understood that with any of these forms, the 25 types of connection sleeves illustrated in Figures 7 to 12 inclusive, may be used instead of the specific type of Figures 5 and 6, which is shown as included in the assembled connections illustrated in all these views.

As was generally stated in the preliminary part of this specification, it will be observed that the invention avoids any direct contact between the metallic parts of the connection, and the ceramic fitting. Moreover, it is not necessary to form the fitting with threads, key-ways, sockets, or projections of any character to interlock with a rigid metallic part. The engagement between the gasket and spout will be found sufficient to transmit rotation of the spout to the sleeve, and to prevent relative rotation of the gasket and spout when the sleeve is being threaded upon the supply pipe. The frictional engagement between the gasket and the spout within its 45 seat is particularly advantageous, and by frictional engagement is meant any suitable engagement which will permit slippage without mutilation of either part, since it permits the final adjustment of the spout, after the parts of the connection are tightened in order to direct the spout properly with reference to the tub, basin, or other fixture in association with which it is set up.

It will be understood, of course, that the 55 invention is not limited to the precise structural details illustrated and described, and where such terms as "spout", "gasket", "pipe" and "sleeve" are employed, to designate conventionally constructed parts, they are to be interpreted as covering any equivalent means accomplishing the desired result. For instance, the invention is useful with any ceramic water supply fitting or lavatory attachment, such as spray heads, faucets, and 60 the like.

I claim:

1. In combination with a pipe, a ceramic spout, a metallic sleeve in said spout, threaded for connection with the supply pipe, a gasket rotatable with said spout and engaged with said sleeve to hold the latter against rotative movement in the spout, said sleeve being adjustable on the pipe through rotation of the gasket by the spout and the sleeve serving to press the gasket against a 75 wall of the spout when adjusted on the pipe.

2. In combination with a pipe, a ceramic spout, a metallic sleeve in said spout threaded for connection with the pipe, a gasket rotatable with said spout and having an aperture 80 into which the sleeve snugly fits, said sleeve being held against rotation in the spout by said gasket and being adjustable on the pipe through rotation of the gasket by the spout, said sleeve serving to compress the gasket 85 against a wall of the spout as the sleeve is adjusted on said pipe.

3. In combination with a pipe, a ceramic spout, a metallic sleeve in said spout, threaded for connection with the pipe, a compressible gasket held frictionally in said 90 spout against free rotation relative thereto and engaged with said sleeve to hold the latter against rotative movement in the spout, said sleeve being adjustable on the pipe 95 through rotation of the gasket by the spout and serving to press the gasket against a wall of the spout when adjusted on the pipe.

4. In combination with a pipe, a ceramic spout, a gasket in said spout, the spout around said gasket closely fitting the latter and thereby holding the gasket against free rotation, a metallic sleeve in said spout 100 threaded for connection with the pipe, said sleeve being fitted into said gasket and connected only through the latter with said spout to be rotated thereby upon the pipe.

5. In combination with a pipe, a ceramic spout, a gasket in said spout, the spout around said gasket closely fitting the latter 110 and thereby holding it against free rotation, a metallic sleeve in said spout, threaded for connection with the pipe, said sleeve being fitted into said gasket and connected only through the latter with said spout to be rotated thereby upon the pipe, the sleeve having peripherally arranged means engaging said gasket for effecting an interlocking engagement of the sleeve with said gasket.

6. In combination with a pipe, a ceramic 120 spout, a gasket in said spout rotatable therewith, a metallic sleeve in said spout, threaded for connection with the pipe, said sleeve being fitted into said gasket and connected only through the latter with said spout to be rotated thereby upon the pipe or the like, the sleeve having a flange adapted to abut a face of said gasket and to force the same longitudinally against a wall of the spout as the 125 sleeve is adjusted upon said pipe, and the 130

flange having thereon means interlocking with the gasket.

7. In combination with a pipe, extending through a wall, a ceramic spout, a metallic sleeve in said spout, threaded for connection with the pipe, a gasket rotatable with said spout and engaged with said sleeve to hold the latter against rotative movement in the spout, said sleeve being adjustable on the pipe through rotation of the gasket by the spout and the sleeve serving to press the gasket against a wall of the spout when adjusted on the pipe, and gasket means around the pipe between the rear end of said sleeve and said wall through which the pipe projects.

8. The combination with a pipe, a ceramic spout, a metallic member adjustable upon said pipe and being entirely free of contact with said ceramic spout at all times, and yielding means forming the sole connection between said member and ceramic spout, and supporting said spout entirely free of contact with said pipe and member whereby rotation of the spout will rotate said member by said yielding means and move said member and spout longitudinally of said pipe.

9. The combination with a conduit, a ceramic spout, and yieldable means forming the sole support of said spout upon said conduit for maintaining said spout spaced from and out of contact with said conduit.

10. A ceramic spout having a bore, a threaded sleeve, and pliable means supporting said sleeve in said bore free from contact with said spout at all times.

11. A ceramic spout having a bore provided with a shoulder, a yieldable gasket larger than the bore having an opening, a sleeve snugly fitting in said opening and held thereby in spaced relation to said spout, and said sleeve having a flange adapted to abut said gasket and move it into engagement with said shoulder.

45 In testimony whereof I have hereunto set my hand.

PHILIP MUELLER.
